CLAIM

I claim the ornamental design for condiment dispenser, as shown and described.

DESCRIPTION

FIG. 1 is a front perspective view of a condiment dispenser incorporating my new design;

FIG. 2 is a top perspective view thereof;

FIG. 3 is a back elevation view thereof;

FIG. 4 is a right side view thereof;

FIG. 5 is a left side view thereof;

FIG. 6 is a front perspective view thereof; and,

FIG. 7 is a bottom perspective view thereof.
